JOHN M. RILEY, OF NEWARK, NEW JERSEY.

Design No. 3,908, dated March 15, 1870.

DESIGN FOR HANDLE-CAP FOR SATCHELS.

The Schedule referred to in these Letters Patent and making part of the same

---

To all whom it may concern:

Be it known that I, JOHN M. RILEY, of Newark, in the State of New Jersey, have invented and produced a new and original Design for a Handle-Cap for Satchels, Carpet-Bags, &c., of which the following is a specification.

My design of a handle-cap consists of a strip of metal, the center of which, *a*, is slightly corrugated, (see Figure II,) and bent in a circular shape, to allow a ring, *n*, attached to the carpet-bag or satchel, to pass through.

The ends *b b'* are bent concave, to form a cylindrical cup, into which the end of the strap *B* is secured. What I claim as my invention, and desire to secure by Letters Patent, is—

The form, shape, or configuration of the handle-cap, as shown and described.

JOHN M. RILEY.

Witnesses:

HENRY E. ROEDER,
JOHN CHRIST.
